CLAIM

I claim the ornamental design for a lippage cap, as shown and described.

DESCRIPTION

FIG. 1 is a top perspective view of a lippage cap.

FIG. 2 is a bottom perspective view of the lippage cap shown in FIG. 1.

FIG. 3 is a top plan view of the lippage cap shown in FIG. 1.

FIG. 4 is a bottom plan view of the lippage cap shown in FIG. 1.

FIG. 5 is a front elevation view of the lippage cap shown in FIG. 1.

FIG. 6 is a right side elevation view of the lippage cap shown in FIG. 1.

FIG. 7 is a left side elevation view of the lippage cap shown in FIG. 1; and,

FIG. 8 is a top perspective view of the lippage cap shown in FIG. 1 with the lippage cap shown in one example of an environment.

The broken lines illustrate environmental subject matter that forms no part of the claimed design.

1 Claim, 4 Drawing Sheets

Related U.S. Application Data

filed on Aug. 11, 2015, now Pat. No. 9,279,259, which is a continuation-in-part of application No. 14/718,131, filed on May 21, 2015, now Pat. No. 9,322,185.
